PUMP

Richard Harland Dickinson, Old Windsor, England, assignor to Hygroequipments Limited, London, England, a British company

Application December 17, 1946, Serial No. 716,832
In Great Britain November 5, 1945

Section 1, Public Law 690, August 8, 1946
Patent expires November 5, 1965

5 Claims. (Cl. 103—75)

1

This invention relates to pumps for liquids and has for its object to provide an improved construction of pump particularly, although not solely, suitable for lifting liquids from a depth, as for example, from a bore hole or well and delivering it at any desired height, such pumps being commonly known as deep-lift pumps.

In the accompanying drawings:

Figure 1 represents a simple form of pump according to this invention.

Figure 2 is a part view showing a modified construction, and

Figure 3 shows another modified construction.

Referring first to Figure 1 a pumping installation comprises a reciprocating pump constituted by a piston 10 driven by any suitable motor 11 and working in a cylinder 12 which is in free communication with a hydraulic pressure-line 13 which extends downwards from the pump 10 to the point from which liquid is to be pumped. At its lower end 14 the pressure-line communicates with a delivery-pipe 15 which extends upwards to any desired height to which the liquid is to be delivered. The pressure-line 13 and the delivery pipe 15 thus constitute a U-tube in which the static pressures of two columns can balance one another according to their respective heights.

At the lower end of this U-tube there is a suction-inlet opening 16 communicating with a valve-chamber 17 in which a non-return valve 18 permits entry of the liquid to be pumped, into the system, but prevents outward flow therefrom. The delivery-pipe 15 is shown as terminating at an outlet 19 which may be at any desired height or location with respect to the piston 10.

The cross-sectional area of the delivery pipe 15 is smaller than that of the pressure line 13.

In the operation of this pump the system is primed by filling it with liquid in any convenient manner; when the piston 10 is reciprocated in the cylinder, on the downward or inward stroke, pressure is applied to the pressure-line so that the liquid is forced down and into the delivery-pipe at the lower end thereof so as to displace the liquid in the delivery-pipe upwards.

The liquid in the delivery-pipe being thereby set in motion at a higher velocity than the liquid in the pressure-line tends to continue in motion when the piston reaches the inner end of its stroke and stops. This continued motion of the liquid in the delivery pipe draws in more liquid past the suction-valve 18 to maintain the pipe-system filled, so that when the piston moves

2

outward on its return stroke the pressure-line is also filled; the next stroke of the piston repeats the operation, and a quantity of liquid, equal to the additional liquid which is drawn in past the suction-valve 18, is expelled through the delivery-pipe on each stroke.

In the modification illustrated in Figure 2 there is provided between the delivery-pipe 15 and the pressure-pipe 13 a cross-connection 20 near the upper ends of the pipes; this cross-connection is situated at a point near the outward limit of movement of the piston 10 so that it is uncovered as the piston reaches the end of its outward stroke and liquid can flow in from the delivery-pipe into the pressure-line to ensure it being filled ready for the next stroke.

Figure 2 also shows another modification in which a non-return valve 21 is provided in the pressure-line near the lower end thereof, this valve being held in its closed position by a spring 22 so as to support to any desired extent the column of liquid above it, whilst permitting free downward flow on the inward stroke of the piston. Since this valve prevents upward flow into the pressure-line, this line is refilled at the end of the outward stroke of the piston 10 through the cross-connection 20.

In the constructions so far described the pressure-line and delivery-pipe have been illustrated as side by side but in an alternative construction illustrated in Figure 3 they may be co-axial constituting a U-tube whereof one limb is inside the other. The pressure-applying device in the system is shown as a piston 10 similar to that already described, but the pressure-line 33 is made of a diameter sufficiently large to accommodate within it the delivery-pipe 34, and the delivery-pipe as already described is of less cross-sectional area than the annular cross-sectional area of the pressure-line 33. The suction-inlet-valve 35 is situated at the lower end of a tapering pipe 36 extending upwards from it into the delivery-pipe 34 and the lower end of the delivery-pipe is open at 37 to the pressure-line 33 so that the operation of this pump is similar to those already described. Communication may be provided under the control of a non-return valve 38 between the delivery-pipe and the pressure-line 33 and cylinder 12.

There may also be provided in connection with the pressure-line 33 the usual type of air-reservoir 39 for equalizing the variations in pressure produced by a reciprocating pump, and it is a feature of the present arrangement that the communication between the pressure-line 33 and

the reservoir 39 is controlled by a manually adjustable valve 40 to suit any particular conditions of operation.

The priming valve 41 may be provided at the upper end of the delivery-pipe.

I claim:

1. In a pump the combination of a cylinder, a piston reciprocable therein, a pressure line extending down from said cylinder to the point from which liquid is to be pumped, a delivery pipe of smaller diameter than said pressure line operatively connected to the lower end thereof and extending upwards to the required point of delivery, an opening at the junction of said pipes to the ambient space constituting the sole inlet 15 for the liquid to be pumped, and a non-return inlet valve in said opening.

2. In a pump according to claim 1 the combination with the said delivery pipe, of an opening therefrom to the upper end of the said pressure 20 line.

3. In a pump according to claim 2 the combination with said opening of a valve movable to permit flow into said pressure line.

4. A pump according to claim 3 wherein the 25

valve is constituted by the piston operating the pump.

5. A pump according to claim 1 wherein the delivery pipe is situated inside the pressure line, and comprising also an air-reservoir communicating with said pressure-line, and an adjustable valve controlling said communication.

RICHARD HARLAND DICKINSON.
